(57) **CLAIM**

The ornamental design for a lens for camera, as shown and described.

DESCRIPTION

FIG. 1 is a front, top, right perspective view of a lens for camera showing the new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines shown in the drawings depict portions of the lens for camera that form no part of the claimed design. The figures are illustrated to show rings of contrasting appearances.

1 Claim, 7 Drawing Sheets
